UNITED STATES PATENT OFFICE

148,193

DESIGN FOR A GOLF CLUB HEAD

Kenneth Smith, Lenexa, Kans.

Application August 23, 1946, Serial No. 132,766

Term of patent 14 years

(Cl. D34—5)

To all whom it may concern:

Be it known that I, Kenneth Smith, a citizen of the United States, residing at Lenexa, in the county of Johnson and State of Kansas, have invented a new, original, and ornamental Design for a Golf Club Head, of which the following is a specification, reference being had to the accompanying drawing, forming a part thereof.

Fig. 1 is an elevational view of one face of a golf club head, showing my new design.

Fig. 2 is an enlarged, fragmentary elevational view of a portion of the face shown in Fig. 1; and

Fig. 3 is a cross-sectional view of an enlarged scale taken on line III—III of Fig. 1.

The characteristic feature of my design resides in the specific surface ornamentation and grooving on the striking face of a golf club head, as shown.

I claim:

The ornamental design for a golf club head, as shown and described.

KENNETH SMITH.
